UNITED STATES PATENT OFFICE.

CHARLES C. DARLING, OF PROVIDENCE, RHODE ISLAND.

DESIGN FOR A BADGE.

SPECIFICATION forming part of Design No. 27,373, dated July 20, 1897.

Application filed June 9, 1897. Serial No. 640,076. Term of patent 7 years.

To all whom it may concern:

Be it known that I, CHARLES C. DARLING, a citizen of the United States, residing at Providence, in the State of Rhode Island, have 5 invented a new and original Design for a Badge or Charm, of which the following is a specification, reference being had to the accompanying drawing.

In the drawing the figure represents the 10 front view of a badge or charm embodying my design.

The leading features of my design consist 15 in the representation of a curved log of wood with an ax and beetle resting upon the log with their handles crossing each other from the inner curved side of the log, the crossing of the handle being covered by a leaf and having an inwardly-directed wedge resting upon the middle portion of the log.

20 In the drawing, A represents the front plate

of a badge, pin, or charm having at its upper side the representation of a curved log *a*, upon which are placed the beetle-head *b* and ax *c*, the handles *d* and *e* of which are arranged in a direction to cross each other from the inner curved side of the log, the crossing of the handles *d* and *e* of the beetle and ax being covered by the representation of a leaf *f*. Upon the middle portion of the log *a*, between the beetle *b* and ax *c*, is represented 25 the inwardly-directed wedge *g*, which either may or may not be provided at its head *g'* with the eye *h*.

What I claim is—

The design for a badge or charm, substantially as herein shown and described. 30

CHARLES C. DARLING.
